LIGHT-DISTRIBUTION CHART.

1,268,440.

Specification of Letters Patent. Patented June 4, 1918.

Application filed August 14, 1916. Serial No. 114,672.

To all whom it may concern:

Be it known that I, HENRY D'OLIER, Jr., a citizen of the United States, residing at Bridgeport, county of Fairfield, State of Connecticut, have invented an Improvement 5 in Light-Distribution Charts, (Case A,) of which the following is a specification.

This invention has for its object to provide a light distribution chart which shall 10 display, in connection with a set of representations of lamp wattage, a set of representations of reflectors, and a set of representations of results obtainable, *i. e.*, indications of different degrees of light concentration and direction, said representations 15 being so arranged as to display, at the intersection of imaginary lines extending through a representation of lamp wattage and through a representation of a result, a representation of the special reflector which, 20 when used in connection with the lamp wattage indicated, will produce the result indicated, *i. e.*, a special concentration and direction of rays of light, and may also display 25 information indications of any character that may be found desirable. In other words, my novel chart enables the user to select at a glance the proper lamp and reflector to produce, when combined, any required 30 concentration and direction of rays of light.

With the above and other objects in view, I have devised the novel light distribution chart of which the following description in 35 connection with the accompanying drawing is a specification, reference characters being used to indicate the several parts:

The drawing is a plan view of a portion 40 of a light distribution chart embodying my novel invention.

10 denotes a card, sheet or folder, which for convenience I will term the sheet, and which may be made of any suitable material, as celluloid, paper or textile material and 45 of any preferred shape, as round or angular. By preference, although not necessarily, the sheet is divided, by lines crossing each other at right angles, into squares. 11 denotes a set of representations of lamp wattage. 50 These representations may be in the form of pictures of lamps or of statements of wattage, as for example "100 watt," or both pictures and statements may be used, if pre-

ferred, as shown in the drawing. As 10, 15 and 20 watt lamps are substantially the same 55 in configuration and arrangement of filament, I have grouped them together. Independent representations of 60, 100, 200 and 500 watt lamps are shown, as these lamps differ more or less in configuration and in 60 the arrangement of the filament.

12 denotes a set of representations of results obtainable in the concentration and direction of rays of light. These representations may be in the form of diagrams indicating different degrees of light concentration, or of words indicating different degrees of light concentration, as "angle," "distributing," "extensive," "intensive," "focusing," &c., or both diagrams and words may be 70 used if preferred, as shown in the drawing. In connection with these representations of results obtainable, I may or may not use letters and figures indicating the mounting height of the lamp above the working plane. 75 For example, the working plane is ordinarily figured as two feet, six inches above the floor, and a standard mounting height, indicated by M, may be arbitrarily fixed at eight feet above the working plane, and the 80 figures used in connection with the letter M indicate the degree of concentration of the rays of light at the working plane, thus M-2 indicates that a lamp in a definite 85 type of reflector eight feet above the working plane will evenly illuminate that working plane over the area of a circle sixteen feet in diameter, the center of the circle being directly under the tip of the lamp hanging pendant. If greater intensity of light is 90 required, another type of reflector must be used, which will produce even illumination over a smaller area; thus, M-1 $\frac{1}{2}$ indicates that a lamp in a definite type of reflector eight feet above the working plane will 95 evenly illuminate the working plane over the area of a circle ten feet in diameter. If still greater intensity of light is required, still another type of reflector must be used that will concentrate the rays of light to a still greater degree; thus, M- $\frac{3}{4}$ indicates that a lamp in a definite type of reflector eight feet above the working plane will illuminate the working plane over the area of a circle six feet in diameter, *i. e.* three-fourths of the 100 standard mounting height.

The rest of the surface of the sheet bears a set of pictures or representations of different styles and sizes of reflectors, indicated by 13. These representations of reflectors 5 are shown as placed in vertical columns in alinement with the representations of lamp wattage and in horizontal lines in alinement with the representations of results obtainable. Contiguous to each reflector, I may 10 or may not place letters and numbers giving certain information and making it unnecessary to refer to a catalogue. For example, H means that the fixtures are Hubbell fixtures; M means porcelain enamel; X means angle 15 position; D means distributing; I means intensive; E means extensive; F means focusing; A means aluminum finish; the number indicates the wattage of the lamp; and L, following the number, means heel extension; 20 thus, H—M—E—500—L would indicate Hubbell fixtures, porcelain enameled, with an extensive type of reflector on a 500-watt lamp with a heel extension.

The use of my novel chart is as follows: 25 Having determined the lamp wattage to be used, and the result, *i. e.* the light concentration required, as indicated by a representation of a result, the operator traces an imaginary line inward from the selected representation of lamp wattage and from the 30 selected representation of a result, and at the intersection of said imaginary lines will be found a picture or representation with accompanying information indications showing 35 the reflector required to produce the desired concentration of light from the lamp selected. For example, suppose that a 100 watt lamp is to be placed ten feet above the working plane and that an aluminum finished 40 reflector giving intensive concentration of lights is required, the operator traces an imaginary line inward from the representation of lamp wattage specifically indicated by *a* and from the representation of 45 a result indicated by *b*, and at the intersection of said imaginary lines he will find a picture or representation of the reflector, specifically indicated by *c*, required to produce the desired result with the selected 50 lamp. It will of course be understood that the size of the chart is limited only by the number of representations of lamp wattage, results obtainable and reflectors that it is desired to illustrate. For the purposes of 55 this specification, I have illustrated a limited number only of representations of lamp wattage, results obtainable and reflectors. It will furthermore be understood that the sizes and styles of lamps are standardized 60 and that the reflectors are scientifically designed to produce predetermined results from standard lamps. By the use of scientifically designed reflectors, properly located with relation to the lamp filament, the light 65 from the lamp is re-directed so as to cause

a surface or working plane to be evenly illuminated over a known area, the area depending of course upon the type of reflector and the height of the lamp above the working plane.

70

Having thus described my invention, I claim:

1. A chart of the character described comprising a set of indications of different fixed light concentrations, a set of indications of 75 different fixed light intensities, and a plurality of indications of devices for obtaining the various indicated light concentrations when employed with the different indicated light intensities, said indications of devices 80 being so arranged that a device capable of producing a selected light concentration will be indicated at the intersection of right angularly disposed imaginary lines leading from any of the indicated light intensities 85 and the selected indication of light concentration.

2. A chart of the character described comprising a row of indications of different light concentrations, a row of indications of 90 different light intensities arranged at right angles to the row of light concentrations, and a plurality of rows of indications of devices for obtaining the various indicated light concentrations when employed in connection with the different indicated light intensities, said indications of devices being so arranged that a device capable of producing a selected light concentration will be indicated at the intersection of right angularly 100 disposed imaginary lines leading from any of the indicated light intensities and the selected indication of light concentration.

3. A chart of the character described comprising a vertically disposed set of different light concentrations, a horizontally disposed set of indications of different light intensities, and a plurality of horizontally disposed sets of indications of devices for obtaining the various indicated light concentrations when employed with the different indicated light intensities, the sets of indications of devices being arranged in alinement with the respective indications of light concentrations and indications of light intensities, whereby a device capable of producing a selected light concentration will be indicated at the intersection of right angularly disposed imaginary lines leading from any of the indicated light intensities 110 and the selected indication of light concentration.

4. A chart of the character described comprising a set of indications of different fixed light concentrations, a set of indications of different fixed light intensities, and a plurality of indications of devices for obtaining the various indicated light concentrations when employed with the different indicated light intensities, said indications of devices 125

115

130

being so arranged that a device capable of producing a selected light concentration will be indicated at the intersection of right angularly disposed imaginary lines leading from any of the indicated light intensities and the selected indications of light concentration, and means for indicating variations in the fixed light concentrations.

5. A chart of the character described comprising a set of indications of different fixed light concentrations, a set of indications of different fixed light intensities, and a plurality of indications of devices for obtaining the various indicated light concentrations when employed with the different indicated light intensities, said indications of devices being so arranged that a device capable of producing a selected light concentration will be indicated at the intersection of right angularly disposed imaginary lines leading from any of the indicated light intensities and the selected indication of light concentration, and means for indicating variations in the fixed light concentrations.

ing variations in the fixed form of the devices to be selected.

25

6. A chart of the character described comprising a set of indications of different fixed light concentrations, a set of indications of different fixed light intensities, and a plurality of indications of devices for obtaining the various indicated light concentrations when employed with the different indicated light intensities, said indications of devices being so arranged that a device capable of producing a selected light concentration will be indicated at the intersection of right angularly disposed imaginary lines leading from any of the indicated light intensities and the selected indication of light concentration, means for indicating variations in the fixed light concentrations, and means for indicating variations in the fixed form of the devices to be selected.
